Peter Neeb

United States Patent Office.

PETER NEEB, OF BUFFALO, NEW YORK.

Letters Patent No. 101,760, dated April 12, 1870; antedated April 5, 1870.

IMPROVEMENT IN CIRCULAR-SAW MILLS.

The Schedule referred to in these Letters Patent and making part of the same.

To all whom it may concern:

Be it known that I, PETER NEEB, of the city of Buffalo, in the county of Erie, in the State of New York, have invented a new and improved Mode of Constructing and operating Circular-Saw Tables; and I do hereby declare that the following is a full, and exact description thereof, reference being had to the accompanying drawings and to the letters of reference marked thereon.

The nature of my invention consists in providing a circular-saw with two independent sliding and adjustable tables so arranged that the circular-saw may run in between them; these tables may either be permanently secured to the main frame of the saw, or may be detachable therefrom.

To enable others skilled in the art to make and use my invention, I will proceed to describe its construction and operation.

Figure 1 is a perspective view of one of the sliding saw-tables.

Figure 2 is a plan view of two sliding saw-tables. A is the main frame of the sliding tables.

A' A' are the frames of sliding tables B B.

The same are provided each with two segments D D.

Said segments, in conjunction with pinions E E, have for their purpose the raising or adjusting of frame A' to any desired angle.

Frame A' is secured to the main frame A by means of hinge-joints, as plainly seen in fig. 1.

B B are two sliding tables; they are sliding in frames A' A', and are provided each with an adjustable gauge,

C. The works that are to be sawed are to be put against said gauges, and the sliding tables are to be pushed toward the saw in order to make the saw cut.

It will be observed that in providing a circular-saw with two tables on the plan of fig. 2, the operator is enabled to saw always with the grain of the wood, which, under circumstances, is of much importance; for instance, in sawing picture frames or gilt moldings, if sawed against the grain the wood is apt to break out on the edges; (*i.e.*, one end is to be sawed on one table and the other end is to be sawed on the other table; both gauges are to be set at corresponding angles.)

D D are two segments secured to frame A', (see fig. 1; they are operated by means of shaft E' and pinions E E, the purpose of which have been heretofore described.

F F are two screw-bolts, (one for each segment;) they have for their object to secure or to prevent the segments from slipping whenever the frame A' is raised by tightening up said bolts, so that their heads will impinge upon the segments, as seen in fig. 1.

Having thus fully described my invention,

What I desire to secure by Letters Patent is—

In combination with a circular-saw, the sliding-table B, frames A A', segments D D, shaft E', pinions E E, and pinch-bolts F F, when constructed and arranged substantially as and for the purpose set forth.

PETER NEEB.
